(57) **CLAIM**

The ornamental design for a flange-mounted grill for fire pit as shown and described.

DESCRIPTION

FIG. 1 is a front upper perspective view of a first embodiment of a flange-mounted grill for fire pit showing my new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a front upper perspective view of a second embodiment of a flange-mounted grill for fire pit showing my new design.

FIG. 9 is a front elevation view thereof.

FIG. 10 is a rear elevation view thereof.

FIG. 11 is a left side elevation view thereof.

FIG. 12 is a right side elevation view thereof.

FIG. 13 is a top plan view thereof; and,

FIG. 14 is a bottom plan view thereof.

The dashed lines shown in the drawings are for purposes of illustrating portions of the flange-mounted grill for fire pit that form no part of the claimed design.

1 Claim, 10 Drawing Sheets
